UNITED STATES PATENT OFFICE.

GALEN W. PEARSONS, OF KANSAS CITY, MISSOURI.

PRESSURE-REGULATOR.

SPECIFICATION forming part of Letters Patent No. 367,232, dated July 26, 1887.

Application filed March 16, 1887. Serial No. 231,118. (No model.)

To all whom it may concern:

Be it known that I, GALEN W. PEARSONS, a citizen of the United States, residing at Kansas City, in the county of Jackson and State 5 of Missouri, have invented certain new and useful Improvements in Pressure-Regulators, of which the following is a specification, reference being had therein to the accompanying drawings.

10 My invention relates to improvements in pressure-regulators for water, steam, gas, &c. The object of my invention is to effect a reduction of the pressure of water, steam, gas, &c., where a higher or greater pressure exists in the mains or boiler than is required for the 15 purposes to which it is to be applied and making such reduced pressure uniform. My invention consists in placing a chamber in juxtaposition and in communication with the 20 pipes leading from the main or other source of supply, the wall or walls of said chamber being made flexible, and connected to a valve which will close the circuit and shut off the flow when the walls of the chamber are distended by the pressure of the water, gas, or 25 steam within the chamber.

In the drawing, which is a vertical longitudinal section through the center of the device, A indicates the pressure-chamber, which 30 may be of any suitable or desirable shape, made in two parts, and the two parts provided at the outer edge with inwardly-projecting flanges a', and at the center with bosses a" integral therewith, and through the ribs which abut, 35 the parts are joined together by bolts or screws a, with any suitable packing material interposed between the two sections, so as to form a tight joint. The walls B and B' of the chamber are made elastic, so that they will be 40 slightly bulged or distended when subjected to internal pressure, but will assume their normal position when the pressure is removed.

C is a T-coupling secured to the wall B', to 45 which are secured the inlet and outlet pipes D and E, respectively. The coupling C is provided with a valve-seat, b, in which is seated the valve e, said valve being connected to a stem, d, which passes through the chamber A, and is secured in or to the wall B by 50 means of the screw-threaded portion e and screw-nut f, or in any other suitable manner. The opening in the lower end of the T-coupling C is made larger than the stem of the valve, so that when the pressure of the liquid,

steam, or gas in the pipe E becomes too great 55 it will escape into the chamber A, distending the walls thereof, which draws the valve e down onto the valve-seat b, and thus cut off the supply from the pipe D. When the pressure has been released or exhausted from the 60 pipe E, the walls of the chamber gradually collapse, forcing a portion of the contents of the chamber out through the opening around the stem d into the pipe E and lifting the valve e from the seat b and placing the pipes 65 D and E in communication again.

The narrow opening around the stem d permits the contents of the chamber to escape without causing a vibrating or flattening action of the sides of the chamber, as is the case 70 with most of the devices of this class now in use.

It will be noticed that the supply-pipe and also the exhaust-pipe are located outside of the chamber, so that all the water, steam, or 75 gas does not have to pass through the chamber, and that the chamber is partially filled at all times with water, gas, &c., thus rendering the device extremely sensitive to variable pressure and causing it to act almost instantly, 80 insuring a reliable pressure-regulator.

Having thus described my invention, what I claim, and desire to secure by Letters Patent, is—

1. In a device for regulating the flow of 85 liquids or vapors, an elastic chamber composed of flexible disks with inwardly-projecting flanges and central bosses integral therewith bolted together, in combination with a valve-stem passing through one of said disks 90 and adjustably secured to the other, and a valve located in a valve-chamber, and the induction and eduction pipes connecting with said chamber, substantially as set forth.

2. The combination, with the disks B B', 95 constructed and secured together substantially as described, of the coupling C, forming a valve-chamber, and provided with induction and eduction pipes, the valve e, valve-stem d, and nut f, substantially as and for the purpose set forth.

In testimony whereof I affix my signature in presence of two witnesses.

GALEN W. PEARSONS.
